Patented Feb. 5, 1918.

UNITED STATES PATENT OFFICE.

OSCAR FICHTENBAUM, OF BROOKLYN, NEW YORK.

CONVERTIBLE SOFA.

1,255,146.

Specification of Letters Patent. Patented Feb. 5, 1918.

Application filed June 22, 1916. Serial No. 105,118.

To all whom it may concern:

Be it known that I, OSCAR FICHTENBAUM, a citizen of Brooklyn, county of Kings, State of New York, residing at 55 Humboldt street, have invented certain new and useful Improvements in Convertible Sofas; and I do hereby declare the following to be a full, clear, and exact description of the invention, such as will enable others skilled in the art 10 to which it appertains to make and use the same.

This invention has relation to convertible sofas, and has for its general object to facilitate the operation of folding and unfolding 15 the extensible sections in the operation of converting the device from a sofa into a bed or vice versa. And to this end the invention resides in constructing the bed frame of three sections, one of which is stationary 20 and secured to the sofa frame, and the others of which are foldable one onto the other and onto the stationary section.

Other objects will appear and be better understood from that embodiment of my invention of which the following is a specification, reference being had to the accompanying drawings forming part hereof, and in which:

Figure 1, is a vertical longitudinal section 20 showing the sections of the bed frame unfolded.

Fig. 2, is a view similar to Fig. 1, but showing the sections folded.

Fig. 3, is a detail side elevation of the 35 mechanism for locking the movable sections one to the other when these are folded.

In the embodiment shown the convertible sofa comprises the usual housing "a" and the sectional bed frame "b." The bed frame 40 "b" may be folded and disposed wholly within housing "a" in which position of adjustment the said frame "b" supports the seat 5. The back 6, is disposed between the complementary ends, one of which is shown 45 and indicated by 7, of housing "a," and a pivotal connection as indicated by 8, is provided between the back 6, and the said ends 7. The rear portion of the seat 5, intersects the arc of movement of the back 6, at a point 50 in oblique alinement with the pivotal connection 8, so that the back 6, when in contact with the seat 5, inclines upwardly and rearwardly and co-operates with the rear cross piece 9, connecting the ends 7, to pro-

vide a space or pocket 10, which accommodates certain constructions of the bed frame "b" hereinafter to be described.

The sections 11, 12, and 13 of the bed frame "b" co-operate, when unfolded, to position the usual bed spring 15, so that the same will support the mattress 16. A portion of the section 11 is rigidly secured to the housing "a" and between the ends 7 thereof. The base frame 17, of section 11, is herein shown as being formed of angle 65 iron, and carries at its outer corner portions a pair of uprights, one of which is shown and indicated by 18. The side rails, one of which is shown and indicated by 19, of section 12, are pivotally connected at one end 70 to the uprights 18, and link connections, one of which is shown and indicated by 20, are made between the adjacent ends of the side rails 19, and the side rails 21 of section 13. Section 13 is made less in length than section 75 12, and the link connections 20 are so proportioned in length as to correspond approximately to twice the thickness of the mattress, so that when section 13, is folded onto sections 12, the rails 21 of the former will be 80 parallel with the rails 19 of the latter, as shown by dotted lines in Fig. 1. When the section 13 is folded onto section 12 as just stated, uprights 22 disposed at the ends of foot rail 23 bear on the rails 19—19 of section 12. In this connection it may be well 85 to state that the rails 19—19, are of angle iron and the base sides of such rails extend outwardly so as to intercept the uprights 22.

In folding sections 12 and 13 onto section 90 11, latch bolts, one of which is shown and indicated by 24, on the rails 19, slide into engagement with detents 25, on the uprights 22 when the sections 12 and 13 move into approximately the vertical position in the 95 operation of folding the said sections onto section 11. This engagement between the latch bolts and the uprights has the effect of locking the sections 12 and 13, one to the other as these move toward section 11. The 100 latch bolts are held against detachment from the rails 19, by pins 26, which pass through slots 27 in the rails 19.

The length of section 12 is greater than the corresponding dimension of section 11, and 105 the link connections 20 are so disposed that the ends of the rails 19 will project for an appreciable distance beyond the links when

the section 13 is folded onto the section 12 so that when the said sections are folded onto the section 11, the projecting end portions, one of which is shown in Fig. 2, and indicated by 28, will bear on the brackets 29 secured to the ends 7, of the housing "a."

One end of spring 15, is connected to the foot rail 23, and the opposite end of said spring is connected to a head rail 30. A 10 pair of arms, one of which is shown and indicated by 31, are connected to the head rail 30 and are pivotally connected as indicated by 32, to a pair of rods, one of which is shown and indicated by 33, secured to the 15 uprights 18, and to uprights 34. The said uprights 34 being positioned at the rear corners of the frame 17.

When the sections 11, 12 and 13 are folded one upon the other the head rail 30 bears on the frame 17 as shown in Fig. 2. But when the said sections are unfolded the head rail 30 is elevated into the plane of the rails 19 and 21. The elevation of the head rail 30 is caused by the movement of section 13, in 25 unfolding from the position shown by dotted lines in Fig. 1. A pair of chains, one of which is shown and indicated by 35, prevent upward movement of the head rail 30 beyond the position just stated. When the 30 sections are folded one upon the other the spring 15, is relaxed. But the unfolding of section 13 operates to tension the said spring. This is because the chains 35 operate to hold the head rail 30 against upward and outward 35 movement during the outward and downward movement necessary to adjust section 13 into horizontal alinement with section 12.

With respect to the position of the parts as illustrated in Fig. 1, it will be observed 40 that the outer end portions of the rails 19 are provided with rigidly attached supports one of which is shown and indicated by 36. The ends of these supports come into contact with the floor and operate to support the section 12, when the same is unfolded, and link connections, one of which is shown and indicated by 37, extend between the lower ends of supports 36, and the supports, one of which is shown and indicated by 38, of section 50 13. The supports 38 are pivotally connected to the rails 21 and the links operate to fold and unfold the said supports during the folding and unfolding of section 13. When the section 13 is unfolded the links 37 55 bear upon the floor and coöperate with the supports 36 and 38 to provide a support common to the sections 12 and 13. When the frame is folded, the links 37 are folded, as shown in Fig. 2, and project upwardly 60 within the housing behind the back 6.

When the parts are arranged as shown in Fig. 2, the outer side of the seat 5, projects a trifle beyond the pivotal connection between the uprights 18 and section 12, and 65 appears continuous or substantially so with

the usual covering of plush, leather or the like, which covers the space between the uprights 18.

In the act of unfolding section 12 seat 5 moves therewith and in so moving is prevented from binding on the uprights by the presence of links 39 and 40 which connect seat 5 with the side rails 19, and which are disposed so as to cause the seat to move relatively to the section 12 during the initial 75 turning movement thereof and finally to hold the said seat suspended and depending from the rails 19 and between the uprights 18 and supports 36 when the section 12 is unfolded. 80

In folding the sections 12 and 13 onto section 11, end extensions 41 of rails 19, tension spring 42 connected to the said extensions and to section 11. This tensioning of the springs 42 operates to prevent free downward and inward movement of the sections 12 and 13 as these approach section 11. 85

When the parts are positioned as shown in Fig. 2, the device may be converted into a bed by engaging the loop 43 of back 6, and 90 causing the said back to move upwardly and outwardly until latch bars, one of which is shown and indicated by 44, engage with keepers 45. In this position of adjustment of the back sufficient space is afforded to 95 permit the operator, on taking hold of a convenient portion of section 12, to unfold the same and section 13 to the position shown by dotted lines in Fig. 1. When the parts are in the last named positions the 100 operator proceeds to disengage the latches 24 from the section 13, after which the said section may be unfolded as previously described and as shown by full lines in Fig. 1. In converting the device into a sofa sections 105 12 and 13 are folded onto section 11. When the parts are so folded pocket 10 accommodates supports 36 and links 37. The back 6, is then permitted to descend after disengaging latch bars 44 from keepers 45. 110

What is claimed as new is:

1. In a combined bed and sofa, the combination of a housing having a back, a folding bed frame, including a stationary section secured to the housing, an intermediate section pivotally connected to the stationary section, an end section connected to the intermediate section and adapted to be folded thereonto and link connections between the end section and one end of the intermediate 115 sections for supporting said sections when the frame is unfolded, said links adapted to extend upwardly within the housing behind the back when the frame is folded. 120

2. In a combined bed and sofa, the combination of a housing, a sectional folding bed frame disposed within the housing, a movable seat mounted on said frame, an inclined back pivotally connected at its upper portion to said housing and having its lower 125 130

free end portion engaging the top of the seat when said frame is in the folded position, said back adapted to be swung upwardly and outwardly, means associated with the back and housing for holding the back in its upper position, and folding link connections between sections of the frame for supporting said sections when the frame is unfolded, said links adapted to extend up-

wardly within the housing behind the back 10 when the frame is folded.

In testimony whereof, I affix my signature, in presence of two witnesses.

OSCAR FICHTENBAUM.
